UNITED STATES PATENT OFFICE

LÉON NAGANT, OF LIÈGE, BELGIUM.

BREECH-LOADING FIRE-ARM.

SPECIFICATION forming part of Letters Patent No. 286,726, dated October 16, 1883.

Application filed March 17, 1881. (No model.) Patented in Belgium May 9, 1876, No. 39,512; in England June 12, 1880, No. 2,389; in Germany August 8, 1880, No. 14,017, and in Austria-Hungary October 12, 1880, No. 33,565, and No. 37,499.

To all whom it may concern:

Be it known that I, LÉON NAGANT, of Liège, in the Kingdom of Belgium, gunmaker, have invented new and useful Improvements in 5 Breech-Loading Fire-Arms, of which the following is a specification.

The invention consists of a new arrangement of mechanism whereby the breech of the arm is firmly closed, the handling made rapid 10 and simple, the dismounting and remounting easily performed, and without any other tool than a plain turn-screw with a single blade.

The breech mechanism comprises a breech-box containing an obturator pivoted upon a 15 transverse axis. A lever pivoting upon another axis takes under the obturator, which it maintains pressed immovably against the faced end of the barrel. In the obturator is placed a striker, pivoting upon a transverse axis 20 placed toward the middle of its length. The head of the striker carries a rear shoulder. In the obturator, where the striker is placed, is a stop, against which the shoulder of the striker abuts. This arrangement limits the 25 backward movement of the striker in the obturator, and prevents it from leaving it even in the case of a violent retrograde effort. In the body of the lever, or at its side, is placed a hammer, intended to act on the striker. It may 30 have the same axis as the lever, or a special one. This hammer, being carried by the lever, cannot reach the striker if the lever has not completely effected the closing by taking entirely under the obturator. A cartridge- 35 extractor is worked by the obturator. It may have the same axis as the latter, or a special one. The arms of the extractor may be furnished with wings (*aillettes*) entering recesses formed in the faced end of the barrel. The 40 arms of the extractor are thus held very firmly, and cannot be displaced or deformed by the effort of the explosion, even if the breech end of the barrel is isolated, instead of being held in a breech-box. The trigger-guard carries 45 the trigger and the mainspring, and may also receive other pieces of the mechanism. It is fixed at one end to the lower tail of the box by means of a screw, upon which it pivots. The body of the trigger-guard is held in place by 50 a screw in the inside of the box. This arrangement allows of withdrawing the trigger-guard,

as well as the pieces of mechanism attached to it, without dismounting the stock. This trigger-guard constitutes, also, a lever, serving for dismounting and mounting the mainspring 55 without the help of a special instrument.

Figure 1 shows the mechanism closed, with the hammer down. The head of the hammer rests against the striker, the point of which projects from the obturator. Fig. 2 shows 60 the mechanism closed, but with the hammer cocked, ready for firing. Fig. 3 shows the mechanism open, with the extractor throwing the cartridge out of the chamber. The point of the striker has been withdrawn into the obturator. This figure also shows the dismounting of the trigger-guard and the pieces connected with it.

Figs. 1, 2, and 3.—A is the obturator; B, axis of obturator and of extractor; C, lever; 70 D, axis of lever and hammer; E, striker; F, axis of striker; E', rear shoulder of striker, (see also Fig. 1^a;) A', part of the obturator which forms a stop, against which abuts the shoulder E' of the striker; E², lower arm of the 75 striker, (in Fig. 1 it is shown protruding from the obturator;) G, hammer, (see also Fig. 1^b;) H, extractor; H', projection, which is acted upon by the shoulder A' of the obturator, causing the extractor to turn over and expel the 80 cartridge from the chamber; I, trigger-guard; K, pivot-screw of the tail of the trigger-guard; L, screw holding the trigger-guard in the breech-box; C', tail of lever; C², head of lever; A³, lower part (or foot) of obturator, against 85 which slides the lever to open the mechanism; A⁴, upper and hinder part of obturator, against which the head of the lever slides, to close the mechanism.

Fig. 4 is a front view of obturator; A², lateral shoulders, acting on extractor; Fig. 5, back view of obturator; C³, recess for the body of striker; Fig. 6, back view of lever; G', recess for the body of the hammer; Fig. 7, front view of extractor; H', lateral projections, acted upon by the obturator; Fig. 8, back view of extractor; Fig. 9, front view of extractor, the arms being furnished with wings H²; Fig. 10, front view of the faced end of the barrel with extractor. The wings H³ of the extractor are 95 lodged in the recesses H³ of the barrel. 100

In order to open the mechanism, the tail of

the lever C' is pushed forward. The head C² of the latter retires from under the obturator, which is thus disengaged. The tail of the lever then meets the lower arm, E², of the 5 striker, which retires into the obturator. The object of this movement is to cause the point of the striker to retire automatically into the obturator. Immediately after, the tail of the 10 lever pushes forward the lower part, A³, of the obturator, of which the upper portion, A⁴, is then turned over backward. By this movement the faced end of the barrel is uncovered, and the obturator, transmitting to the extractor the impulse that it has itself received from the 15 lever, forces the extractor to throw the cartridge-case out of the chamber. At the same time the lever has fully cocked the hammer. The hammer can be also cocked and uncocked by its crest independently of the lever. The 20 hammer has also a notch for half-cocking. In order to reclose the mechanism, the tail of the lever (or the foot of the obturator) is moved backward. The head of the latter, sliding against the upper and hinder part, A⁴, of the 25 obturator, pushes the latter against the faced end of the barrel. Arrived at this point the head of the lever takes under the obturator and prevents it absolutely from being opened by the explosion of the cartridge, the hammer remaining at full-cock, ready to act upon the striker.

The mechanism also comprises a piece serving two purposes. It is constructed as follows, (see Figs. 11 and 12.) A bar, M, is applied to the external side of the breech-box, the end of 35 which, being bent to a right angle, is prolonged into a cylindrical stem, N, traversing the breech-box above the upper branch of the mainspring. The outer bar covers the pivots of the obturator and lever, to prevent 40 them from coming out of the box. (See Fig. 2.) At the middle of the stem N, opposite the mainspring, is formed a notch, O. When the outer bar is placed so as to cover the pivots of the obturator and lever, the notch O in the stem 45 faces the mainspring, which it leaves free to act upon the hammer. (See Figs. 2 and 3.) If the outer bar is turned, the hammer being down, the cylindrical part of the stem replaces

the notch, and, forming an eccentric, presses on the mainspring, taking the pressure of this 50 last off the hammer and its axis, thereby facilitating the operation of dismounting and remounting the arm.

The new points as applied to breech-loading fire-arms in the invention are—

1. The arrangement and combination of the obturator A, pivoting upon an axis and formed with a hinder projecting part, A⁴, at its upper end, and with a downwardly-projecting part, A³, at its lower end, with the lever C, pivoting 60 upon another axis, and so formed and adapted that its lower part acts upon the part A³ of the obturator to open the same, and its upper part, C², acts upon the upper part, A⁴, of the obturator, first, to close the same against the faced 65 end of the barrel; and, secondly, by taking under the projecting part A⁴ thereof, to hold or lock the same firmly in position, so as to prevent it from being opened by the explosion of the cartridge, as hereinbefore described, and 70 shown in Figs. 1, 2, 3, 4, 5, and 6 of the drawings annexed.

2. The bar M, adapted to press against the outside of the breech-box for the purpose of keeping the pivots or axes of the obturator and lever in place, such bar M being provided with a cylindrical stem, N, passing through and turning in the breech-box above the upper branch of the mainspring, and having formed in it a notch, O, which allows the mainspring 80 to act when the said bar M is placed so as to cover the said pivots and the notch O comes opposite the mainspring, as shown in Fig. 2, but prevents the action of the mainspring and sets both the hammer and its axis free when 85 the bar M and stem N are turned round into the position shown in Fig. 1, whereby the taking to pieces and putting together of the parts are facilitated, as hereinbefore described, and shown in Figs. 1, 2, 3, 11, and 12 of the drawings annexed.
